UNITED STATES PATENT OFFICE.

MORRIS POLLAK, OF NEW YORK, N. Y.

WATCH-CHAIN HOOK.

Specification forming part of Letters Patent No. 58,287, dated September 25, 1866.

To all whom it may concern:

Be it known that I, MORRIS POLLAK, of the city and State of New York, have invented, made, and applied to use a certain new and useful Improvement in Hooks for Watch-Chains; and I do hereby declare the following to be a full, clear, and exact description of the same, reference being had to the annexed drawings, making part of this specification, wherein—

Figure 1 is a side view of my improved hook as closed. Fig. 2 is an edgewise view of the same as open, and Fig. 3 is a similar view as closed. Fig. 4 is a side view of a slight modification of the said hook, and Fig. 5 is a view of the same edgewise and open.

Similar marks of reference denote the same parts.

The hooks for connecting watch-rings to the chains have been made in a variety of ways, usually however with a hinged swivel, held together by a nut; and in some instances double hooks have been employed that can be turned apart by the hooks moving parallelly to the plane on which they separate; but these are liable to become unhooked.

The nature of my said invention consists in a divided hook, the points of which stand in opposite directions, and the parts are united by a rivet or pin, so that the hooks move apart sidewise. Hence when the ring of the watch is entered it has to be hooked one way into one hook and then the other way into the other hook, after which the hook is closed, and the action of the ring of the watch is to keep the hooks closed.

In the drawings, *a* and *b* are the hooks,

united by the cross-pin or rivet *c*, so that the hooks can be opened by turning them sidewise bodily as they swing upon said pin *c*. The hooks stand with their points in opposite directions, and the shank of one hook has an offset, against which the point of the other hook closes, so that the hook, when closed, shall present a smooth surface, so as not to be opened by anything catching into the point of the hook.

This improved hook may be made, as shown in Figs. 4 and 5, with a swivel-ring, *d*, at its upper end for the watch-chain to be attached to; or it may be made with a second pair of hooks for this purpose, as seen at *e* and *f*, Figs. 1, 2, and 3.

By this mode of construction it is almost impossible for the watch to become accidentally disconnected from the chain; but when the hooks are purposely separated by the introduction between them of the edge of the nail or a knife the watch-ring may be unhooked.

What I claim, and desire to secure by Letters Patent, is—

The hook for watch-chains and other articles, formed double, with the points standing in opposite directions, and attached to each other by a pin or rivet that allows said hooks to separate sidewise, in the manner and for the purposes set forth.

Dated this 21st day of April, 1866.

MORRIS POLLAK.
